UNITED STATES PATENT OFFICE.

LUTHER H. ROWELL, OF SOUTH THOMASTON, MAINE.

BUSH-HAMMER.

SPECIFICATION forming part of Letters Patent No. 396,174, dated January 15, 1889.

Application filed March 22, 1888. Serial No. 268,115. (No model.)

To all whom it may concern:

Be it known that I, LUTHER H. ROWELL, of South Thomaston, in the county of Knox and State of Maine, have invented a new and 5 Improved Bush-Hammer, of which the following is a full, clear, and exact description.

My invention relates to hammers for dressing stone, and has for its object to simplify the construction and impart greater strength 10 and durability to the tools.

The invention consists in the construction and combination of the several parts, as will be hereinafter fully set forth, and pointed out in the claims.

15 Reference is to be had to the accompanying drawings, forming a part of this specification, in which similar letters of reference indicate corresponding parts in all the figures.

Figure 1 is a perspective view of the hammer with wrench shown in its position by the dotted lines. Fig. 2 is a cross-section of Fig. 1 through the thimble and handle. Fig. 3 is a perspective view of a modified form of my invention, shown as used for peen-hammers. 25 Fig. 4 is a section of Fig. 3 on the line xx' , Fig. 3; and Fig. 5 is an end view of the shank-sections.

Bush-hammers as heretofore made consist of a central body called the "pole," through 30 which is an eye for the handle, the pole being provided at its ends with channels for holding the cuts or chisels, a separate set of which are required at each end of the pole, the cuts being held in place by bolts and nuts, usually 35 four in number, two of which are passed through holes in the pole and cuts in each channel. The poles also require gibs or stays at the sides of the channels or seats to prevent lateral motion of the cuts. The cuts so 40 made are small and liable to break away at the bolt-holes and work loose in wear by reason of the proximity of the holes to the ends of the cuts.

In my improvement I make use of two 45 pole-plates and shank-sections integral with the plates, which sections are united by a sleeve, which forms a socket for the handle, and instead of using small cuts I make the cuts in the form of long blades, each in one piece and extending through, between,

and beyond the pole-plates, the plates and cuts being secured together by transverse bolts, the heads of which are partly received in square recesses or countersinks, as shown in Fig. 2, which hold the bolts from turning 55 and permit the bolts to be turned when one side becomes worn or flattened.

The pole-plates B are flat rectangular metal plates, from each of which extends medially from one side a substantially semi-cylindrical section, a, forming one-half of the shank D, which sections are correspondingly tapered and threaded at the outer end, at E, to receive the tapering internally-threaded sleeve or thimble, F, which sleeve, when screwed to 60 place on the sections a, binds the same firmly together and provides a socket to receive the end of the handle g. The plates B are provided on each end with two correspondingly and accurately spaced holes to receive the 65 fastening-bolts c. The meeting edges of the shank-sections a are beveled, as shown most clearly in Fig. 5, which construction forms a dovetail lock and prevents lateral movement of the plates and cuts. 75

The cuts A, as shown in Fig. 1, are made in the form of plates of greater length than the pole-plates, and are provided with holes corresponding with the holes in the plates.

In putting together the several parts one 80 pole-plate is placed upon its outer face with the bolts in position therein, and the cuts in the desired number are placed on the bolts. The other plate is then put in place and the nuts put on the bolts. The sleeve is then screwed 85 over the ends of the sections a, the handle inserted, and the nuts and sleeve tightened up. To facilitate turning the screw, a wrench, H, provided with a curved prong, h, is provided, the end of the prong being inserted in 90 an aperture, k, in the sleeve. This construction provides for the use of a single heavy cut to form a peen-hammer, as shown at A' in Figs. 3 and 4. Peen-hammers as now constructed soon become worn at the edges; but 95 with this construction by providing a new cut the hammer is made as good as new at but slight expense. Figs. 3 and 4 illustrate also a modification, in which a gib, L, is made integral with one plate and enters a slot, b, in 100

the other plate, which gib and slot are preferably dovetailed in form, as shown. This form is illustrated in use as a peen-hammer, but is applicable for use with cuts, especially when intended for use in rough or heavy work.

Having thus fully described my invention, what I claim as new, and desire to secure by Letters Patent, is—

1. In a bush-hammer, the combination, with two pole-plates provided each with spaced bolt-holes and a shank-section tapered and threaded at the outer end, of a tapering threaded sleeve and fastening-bolts, substantially as shown and described.
2. In a bush-hammer, a rectangular plate provided with a semi-cylindrical shank-section tapered and threaded at its outer end, and with spaced bolt-holes, substantially as shown and described.

3. The combination, with two pole-plates 20 formed with shank-sections and provided with spaced bolt-holes, of cuts held between the plates, a sleeve engaging the shank-sections, and fastening-bolts, substantially as shown and described.

4. A bush-hammer pole comprising the separate and independent apertured pole-plates, each having shank forming a half-socket on its inner edge, a transverse integral gib extending inwardly from the outer edge of one 30 plate, the outer edge of the opposite plate having a transverse recess receiving the end of said gib, and a sleeve surrounding the two-part handle socket, substantially as set forth.

LUTHER H. ROWELL.
